UNITED STATES PATENT OFFICE

ALBERT RAMSEIER, OF ZURICH, SWITZERLAND, ASSIGNOR TO ALBERT QUENDOZ, OF ZURICH, SWITZERLAND.

THREAD KNOTTING DEVICE

Application filed May 28, 1930, Serial No. 456,431, and in Switzerland June 20, 1929.

For tying knots, particularly weavers' knots, by mechanical means, a great number of apparatus is known. Most of them are complicated and, therefore, not easy to be handled. Furthermore, these apparatus very often fail to effect the standard weaver's knot in as much as they do not satisfy all the conditions which an operator is required to meet for making the said knot by hand. For this reason the operation of the known apparatus is unreliable. Moreover, with the hitherto known contrivances very fine threads, for example, of artificial silk are not effective in reliable manner and, besides, such threads are even difficult to be tied to knots in workman-like fashion by hand.

When a weaver's knot is to be tied by hand the two thread ends to be united are preferably at first combined by looping; whereupon the thus formed knot is tightened. When the tightening operation is closely watched it will be observed that, for instance, with the usual procedure of tying both short ends of the two threads are held between two fingers of the one hand whilst in the meantime the one thread is gently tightened with the other hand in order to minimize the formed loop. After the loop has become very small the short end belonging to the thread which was tightened is given free and the latter further tightened until the knot is completed. Subsequently the other short end is given free and the other thread tightened. The object of the present invention is to eliminate the above-mentioned disadvantages of the known constructions by closely following the just described knotting operation.

According to the invention in a thread knotting device means are provided for accommodating the crossed threads to be tied in a knot in a receiving member and to secure them therein during the knotting operations as well as movable members for forming a loop with the one thread and hooklets with both thread ends. This device is distinguished by cutting members for cutting the thread ends previous to the knotting to the proper length, further by two spring influenced clamping members for holding the thread ends after the formation of the loop and the

hooklets, and by means for actuating the clamping members, suchwise, that in tightening the one thread to be formed in a loop the clamping member holding the end of the tightened thread is first opened and the other clamping member is only opened after the weaver's knot is correctly formed.

In the accompanying drawings a constructional form of the invention is illustrated, wherein

Fig. 1 is a top plan view of the device and Fig. 2 a side elevation thereof;

Fig. 3 is a fragmentary longitudinal section through the device showing the rear part of the same;

Fig. 4 is a side elevation of the rear part of the device with the lateral guard plate removed;

Fig. 5 is a top plan view of the rear part of the device, partly in section;

Fig. 6 is a section similar to Fig. 3, with parts of the device in the one working position;

Figs. 7 and 8 are sections of details;

Fig. 9 is a section on the line II—II in Fig. 1;

Figs. 10 to 16 illustrate schematically the formation of the loop, and

Fig. 17 shows the finished weaver's knot.

On the base 1 a guide member including two guide rails 2 is arranged along which the carriage 3 is slideable. The carriage is provided with a clamping appliance for the thread having a clamping lever 6 which is acted upon by a leaf spring 4 and turnable about a pivot 5. The lever 6 provided with a handle 7 cooperates with a clamping jaw 8. Opposite the handle 7 of the lever 6 a handle portion 9 is fixed to the carriage, whereby the clamping appliance is conveniently operable with two fingers. The handle 7 projecting above the handle portion 9, the lever 6 is enabled to be conveniently turned against the action of the spring 4 and the thread to be laid in a groove 10 of the clamping jaw 8, whereupon the two handles are pressed together with two fingers in order to hold the thread and at the same time displace the carriage 3 in its guide on the base 1.

When shifting the carriage in the direction

of the arrow 11 (Fig. 6) the front face of the clamping jaw 8 bears on a guide ledge 12 of a pivotal flap 13 and on the continuation of the shifting slides along the ledge 12 after the pivotal flap, normally assuming a tilted position by the influence of the spring 14, is brought in its position shown in chain lines in Fig. 9. Besides, the pivotal flap is provided with a longitudinal groove 15 for the thread. The further movement of the carriage 3 actuates two thread looping arms 16, 17. These arms are tilttable round a common pivot 18 secured to the base 1 and are held apart in their respective inoperative positions by a spring 19. The base 1 is further provided with a block 20 for receiving the thread the upper side of which is formed with a longitudinal recess 21, a transverse incision 22, and an oblique incision 23 disposed on the left half of the block only. The incision 23 is so directed as to communicate with the recess 21 adjacent the place where the latter is crossed by the transverse incision 22.

In the recess 21 a tappet 24 is linked to a pin 25. The tappet 24 is provided with a finger 26 which is held in its vertical inoperative position, as shown in Fig. 3, by over-weight of the other finger 27 of the tappet. By shifting the lever 28, which is turnably mounted on a slide 33 on a pin 32 thereof and influenced by the spring 29, in the direction of the arrow 30 (Fig. 3) the tappet 24 is turned about the pin 25 in the direction of the arrow 31 into its horizontal position indicated in chain lines in this figure. The recess 21 has a depressed portion so as to accommodate the finger 26 in the said position, suchwise, that the lever 28 when further shifted is adapted to pass over the tappet 24. The finger 26 has just such a length that when lowered its front portion extends over the crossing of the recess 21 and the incision 22. The slide 33 is displaceable along two guide bars 34, its movement being limited on the one side by the block 20 and on the other side by the stop 35. The underside of the slide is provided with a recess 36 in which a push-bolt 37 is longitudinally displaceable. The latter is formed with a slot 38 which cooperates with a pin 39 traversing the same for suitably limiting the movement of the bolt relatively to the slide. The slide is provided with two lateral projections 40 to which two pushers 41 are linked. The push-bolt 37 has a forward wedge-shaped portion 42 for co-operation with an inclined portion 43 on a block 44. When the slide is moved in the direction of the arrow 30 the push-bolt 37 is not entrained thereby until the pin 39 is shifted for the length of the slot 38.

In this moment the slide has arrived in its position, as shown in chain lines in Fig. 3. On further shifting the slide in the same direction the push-bolt 37 moves in unison therewith so as to raise the block 44 by means

of its wedge shaped front part (Fig. 7) and to hold it at the end of the shifting movement in the raised position, as shown in Fig. 8. To the block 44 two clamping members for the thread 45 and 46 and two push rods 47 and 48 are connected.

The clamping members and push rods are inserted in corresponding vertical bores 45', 46', 47' and 48' of the block 20 (Fig. 5). As the two push rods 47 and 48 are fixed to the block 44 they provide guidance for the said block. The clamping members as well as the push rods project from the lower side of the base. The coil spring 50 on the push rod 47 tends to press the same together with the block 44 and the push rod 48 downwardly. When the block bears on the base 1 the appurtenance comprising it is in inoperative position. The clamping members 45, 46 for the thread are each displaceable in their respective bores of the block 44 by means of downwardly extending shanks and are engageable to partake in the upward movement of the block 44 against the action of correlated coil springs 49, 52, by means of studs 51 and 51' respectively passed through the said shanks.

The hammer-shaped heads of the clamping members 45 and 46 in their inoperative positions rest on the upper side of the block 20 and are adapted for special purposes to be moved upwardly independently of each other or of the block 44. On both sides of the block scissors are arranged for cutting the thread ends to be tied in a knot to the desired length. Each pair of scissors comprises two blades 54, 55 pivoted to the block 20 by means of a pin 53. Each blade is provided below its fulcrum with a crescent shaped portion 56 and 57 respectively which is surrounded by a semi-circular extension 58 and 59 respectively of a lever 60. Between the extensions 58 and 59 a wedge portion 61 is formed on the lever 60 which on turning the lever about a pivot 63 on the block 20 in the direction of the arrow 62, separates the crescent shaped portions and, thereby, closes the scissors. When the lever is turned in the opposite direction to the arrow 62 the extensions 58 and 59 of the lever press on the portions 56 and 57 of the scissor blades 54 and 55, thus causing the scissors to open.

The underside of the lever 60 is provided with a slanting portion 64 for the wedge shaped front part 65 of the respective pusher 41 to slide on (when the slide 33 moves in the direction of the arrow 30) in order to cause the lever to move upwardly and the scissors to close.

During the rearward motion of the slide 33 the slanting portion 66 on the upper side of the pusher in connection with the arm 67 of the lever 60 effects the resetting of the latter into inoperative position. The scissor mechanism is protected by a guard plate 68 secured

to the block 20. In a pocket 69 of the guard plate a coil spring 70 is housed for exerting the necessary side pressure on the scissor blades for effecting a clean cut on the thread.

5 To enable the thread to be held fast previous and during the knotting operation the base 1 is further provided with three stationary clamping appliances. In line with the incision 22 the clamping appliances 71 and 72 are disposed and to the left hand side (seen from the operating end of the device) and in line with the incision 23 the clamping appliance 73 is placed. These further clamping appliances comprise a fixed leg 74 and a 10 spring pressed turnable leg 75.

15 The operation of the device for effecting a weaver's knot is as follows:

The two threads to be joined are designated with A and B and their ends to be tied to a 20 knot with *a* and *b* respectively. At first the thread A is clamped to the device with its free end *a* inserted in the clamping appliance 73 (Figs. 10 and 12) wherefrom it is passed through the incision 23, recess 21, and the 25 groove of the pivotal flap 13 to the clamping appliance 6, 8 to bear on the curved part of the guide ledge 12. The second thread B is then placed in the incision 22 with its free end *b* inserted in the clamping appliance 72, whereupon the knotting operation may begin 30 by quickly shifting the slide 33 with the one hand in the direction of the arrow 30 (Fig. 3) until it hits on the block 20. By this movement three subsidiary motions are initiated. 35 In the first place the finger 26 is turned down by the lever 28 in order to hold the threads at their point of crossing. Then the scissors are closed in the manner described above and thereupon the clamping members 45 and 46 40 and the push rods 47 and 48 raised. The raising of the push rods erects the thread ends *a*, *b*, cut by the scissors to a vertical position so as to project somewhat above the block 20 (Fig. 13).

45 Afterwards the clamping appliance 6, 8 is gripped with the other hand by the handles 7 and 9 and displaced in the direction of the arrow 11 (Fig. 12). During this movement the tilttable flap is turned into its vertical position, as indicated in chain lines in Fig. 9, and at the end of the movement the thread portion positioned in the groove of the tilttable flap is formed in a loop *c* (Figs. 6 and 14).

50 The front parts of the clamping members 6 and 8 are so far entered in the recess during this movement until they butt against the front part of the lever 28. On further shifting the carriage 3 the lever 28 is pushed back and the slide 33 together with it. Soon after the abovesaid abutting the lower portions of the carriage 3 hit on the lower portions of the thread looping arms 16, 17, thus causing the latter to move in the direction of the arrows shown in Fig. 12, whereby the said arms

55 grip the projecting thread ends *a'*, *b'* and lay them under the respective thread clamping heads 45, 46. At this time the carriage 3 is so far advanced that the said heads by action of the springs 49, 52 fall back to hold the 60 thread ends underneath them. Thereupon the carriage 3 is retracted and the thread A entrained to move together with it (Fig. 16) so as to tighten the loop *c*, whereby the thread end *a'* jammed by the clamping head 46 is 65 first pulled. In order to release the thread end *a'* at this time and before the other end *b'* is released it is necessary that the spring 52 is weaker than the spring 49. Otherwise 70 the formation of a weaver's knot would be rendered impossible and a faulty knot or no knot at all would result. On further retracting the carriage 3 the thread end *b'* is then 75 released from the corresponding clamping head whereafter the knot is finished as soon as the carriage is arrested by the extreme stop member. Fig. 17 illustrates the knot 80 completely formed but not entirely tightened. In this position of the parts the device is in 85 readiness for starting a fresh knot.

90 Due to the fact that the scissors cut the thread ends every time to the correct length all the knots are formed with free thread ends of uniform extent which is such that a subsequent trimming of the said ends is 95 not necessary. It is obvious that the possibility of effecting weavers' knots of uniform size and shape is of considerable advantage for the weaving and similar industries. Experience has shown that the described device 100 permits of constantly effecting workmanlike weavers' knots even with the finest threads of artificial silk. This also is a very valuable result.

105 Naturally many details of the described device may be varied; for instance, the carriage 3 and the slide 33 could be interconnected by suitable members in such manner that the movement either of the carriage or the slide alone or of some additional control member would initiate the different working 110 incidences necessary for the knotting. Moreover, the two hammer shaped thread clamping members 45 and 46 instead of being provided with unequal springs might be suitably alternately actuated by means of cam disks or the like which were rotated by the movement of the carriage 3. This design would eliminate the drawbacks arising from the relaxation 115 of the springs and the necessity of regularly controlling the tensioning of the same without substantially complicating the construction of the device.

120 I claim:

125 1. In a device for tying threads in a weaver's knot, in combination, a bed for accommodating the threads in intercrossed position, a clamping appliance for the one thread displaceable relatively to said bed for forming a loop with this said thread about the other,

thread cutting means combined with said bed and adapted to cut the ends of the crossed threads in the requisite length for the finished knot to be formed, means for holding the crossed threads against said bed at their place of junction while said loop is formed, means for bending the cut thread ends into the form of a hooklet and releasable clamping means for said hook-shaped thread ends.

2. In a device for tying threads in a weaver's knot, in combination, a bed for accommodating the threads in intercrossed position, a clamping appliance for the one thread displaceable relatively to said bed for forming a loop with said thread about the other, thread cutting means combined with said bed and adapted to cut the ends of the crossed threads in the requisite length for the finished knot to be formed, means for holding the crossed threads against said bed at their place of junction while said loop is formed, means for bending the cut thread ends into the form of a hooklet, a base for said bed, a hammer-shaped clamping head for each hook-shaped thread end, a shank provided on each clamping head and extending through a through-bore in said bed beyond the underside of said base, two compression springs of different strength, one for each shank to surround the same between the underside of said base and the lower end of the shank for urging said clamping heads against said bed into locking position with different pressure adapting said heads to release the thread ends successively and releasing means for said clamping heads.

3. In a device for tying threads in a weaver's knot, in combination, a bed for accommodating the threads in intercrossed position, a recess in said bed, a pivot pin crossing said recess, a tappet swingably mounted on said pivot pin, two fingers constituting said tappet, the one being held inoperative in upstanding position by overweight of the other, a clamping appliance for the one thread displaceable relatively to said bed for forming a loop with this said thread about the other, thread cutting means combined with said bed and adapted to cut the ends of the crossed threads in the requisite length for the finished knot to be formed, a slide cooperating with said bed, a spring influenced lever provided on said slide and adapted to swing said tappet into horizontal position to hold the crossed threads against said bed at their place of junction while said loop is formed, means for bending the cut thread ends into the form of a hooklet, and releasable clamping means for said hook-shaped thread ends.

4. In a device for tying threads in a weaver's knot, in combination, a bed for accomodating the threads in intercrossed position, a clamping appliance for the one thread displaceable relatively to said bed for forming a loop with said thread about the other, thread cutting means combined with said bed and

adapted to cut the ends of the crossed threads in the requisite length for the finished knot to be formed, means for holding the crossed threads against said bed at their place of junction while said loop is formed, push-rods 70 slidable in bores of said bed push-rods for upturning the cut thread ends into the form of a hooklet, a carrier-block for said push rods, a spring cooperating with said push rods to urge the same downwardly in said bed into inoperative position together with said block, a slide cooperating with said bed, a push-bolt yieldingly connected to said slide, a wedge-shaped front portion on said push-bolt to grip under said block for operating said push rods against the action of said spring, and releasable clamping means for said hook-shaped thread ends.

5. In a device for tying threads in a weaver's knot, in combination, a bed for accommodating the threads in intercrossed position, a clamping appliance for the one thread displaceable relatively to said bed for forming a loop with said thread about the other, thread cutting means combined with said bed and adapted to cut the ends of the crossed threads in the requisite length for the finished knot to be formed, means for holding the crossed threads against said bed at their place of junction while said loop is formed, push rods 85 slidable in bores of said bed for upturning the cut thread ends into the form of a hooklet, a carrier block for said push rods, a base for said bed, a hammer-shaped clamping head for each hook-shaped thread end, a shank provided on each clamping head, a stop pin passed through each shank, and cooperating with the through-bore in said bed for each shank to extend therethrough beyond the underside of said base, two compression 90 springs of different strength, one for each shank to surround the same between the underside of said base and the lower end of the shank for urging said clamping heads against said bed into locking position, and guide surfaces in said carrier block for the shanks of said clamping heads to pass through adapting said block to release said clamping heads by engagement with said stop pins against the action of said compression springs and adapting said clamping heads to be locked by said springs independently of said block.

6. In a device for tying threads in a weaver's knot, in combination, a bed for accomodating the threads in intercrossed position, a clamping appliance for the one thread displaceable relatively to said bed for forming a loop with this said thread about the other, thread cutting means combined with said bed on either side thereof and adapted to cut the ends of the crossed threads in the requisite length for the finished knot to be formed, two scissor blades for each clamping means, a crescent shaped extension on each 125 130

blade, a common pivot pin for the blades disposed intermediate of the point and the extension of the blades, an actuating lever for said blades cooperating with said crescent-shaped extensions on each side of said bed, a slide cooperating with said bed, pushers connected to said slide for engagement with said actuating levers, means for holding the crossed threads against said bed at their place of junction while said loop is formed, means for bending the cut thread ends into the form of a hooklet, and releasable clamping means for said hook-shaped thread ends.

7. In a device for tying threads in a weaver's knot, in combination, a bed for accommodating the threads in intercrossed position, a clamping appliance for the one thread displaceable relatively to said bed for forming a loop with this said thread about the other, thread cutting means combined with said bed on either side thereof and adapted to cut the ends of the crossed threads in the requisite length for the finished knot to be formed, two scissor blades for each clamping means, a crescent shaped extension on each blade, a common pivot pin for the blades disposed intermediate of the point and the extension of the blades, an actuating lever for said blades cooperating with said crescent-shaped extensions on each side of said bed, semi-circular portions on said lever each surrounding one of said crescent-shaped extensions for opening the scissors, a wedge-shaped portion on said lever for closing said scissors by moving the extensions apart, a slide cooperating with said bed, pushers connected to said slide for engagement with said actuating levers, means for holding the crossed threads against said bed at their place of junction while said loop is formed, means for bending the cut thread ends into the form of a hooklet, and releasable clamping means for said hook-shaped thread ends.

In testimony whereof I have signed my name to this specification.

ALBERT RAMSEIER.
